Primary Examiner — Jennifer L Watkins*Assistant Examiner* — Samantha Lynne Brodowski(74) *Attorney, Agent, or Firm* — NIXON & VANDERHYE P.C.(57) **CLAIM**

The ornamental design for a satchel, as shown and described.

DESCRIPTION

FIG. 1 is a perspective view of a satchel showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the claimed surface of the shoulder strap depict stitching and form no part of the claimed design. The broken lines showing internal portions underneath the closure flap in FIGS. 4, 5 and 7 depict portions of the article and form no part of the claimed design.

1 Claim, 7 Drawing Sheets**FIG. 1**

FIG. 2

FIG. 3

FIG. 4

FIG. 5

FIG. 6

FIG. 7
